(57) **CLAIM**

The ornamental design for a pot for LED artificial tree, as shown and described.

DESCRIPTION

FIG. 1 is a front, right, and top perspective view of a pot for LED artificial tree, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged portion view of encircled portion labeled for FIG. 9 in FIG. 1; and,

FIG. 10 is another front, right, and top perspective view of the pot for LED artificial tree, shown in use.

The portions of the pot for LED artificial tree shown in broken lines form no part of the claimed design. The broken lines showing a tree, plug, and cord in FIG. 10 are included as environmental structure that form no part of the claimed design.

1 Claim, 10 Drawing Sheets(56)
